UNITED STATES PATENT OFFICE

91,749

DESIGN FOR A VELOCIPED

Bert J. Anderson, Hammond, Ind.

Application November 25, 1933, Serial No. 49,865

Term of patent 14 years

To all whom it may concern:

Be it known that I, BERT J. ANDERSON, a citizen of the United States, residing at Hammond, in the county of Lake and State of Indiana, have invented a new, original, and ornamental Design for a Velocipede, of which the following is a specification, reference being had to the accompanying drawing, forming part thereof.

slightly above the velocipede, showing my new design.

I claim:

The ornamental design for a velocipede as shown.

BERT J. ANDERSON.
